UNITED STATES PATENT OFFICE

RICHARD P. SECKENDORF, OF SOMERVILLE, MASSACHUSETTS, ASSIGNOR TO THE CAMBRIDGE PAPER BOX CO., OF CAMBRIDGE, MASSACHUSETTS, A CORPORATION OF MASSACHUSETTS

MACHINE FOR COVERING BOXES

Application filed June 29, 1929. Serial No. 374,871.

My invention aims to provide a novel machine for covering boxes in the manufacture thereof, and more particularly what are known as paper boxes, wherein the walls comprise a foundation of paper stock or other suitable material which is covered with paper or its equivalent.

My invention is addressed more particularly to the problem of covering boxes of octagonal or other shape that present oblique walls to be covered.

Practicable machines for covering rectangular boxes have long been known in the art, but prior to my invention, so far as I am aware, there has been no practicable machine that would cover boxes presenting oblique side walls.

My invention will best be understood from a description of an illustrative embodiment thereof, shown in the accompanying drawings.

Referring to those drawings:—

Fig. 1 is a side elevation of a preferred type of machine illustrating my invention; Fig. 2 is a right hand view on an enlarged scale of the middle portion of the machine shown in Fig. 1;

Fig. 3 is a plan view in partial section of some of the operating connections shown in Fig. 2;

Fig. 4 is a detail showing in plan view the several brushes and wipers for acting upon the cover blank to lay the same against the walls of the box;

Fig. 5 shows the box positioned upon the blank as it would appear preparatory to the wiping or covering operation;

Fig. 6 is a perspective of the box and cover blank shown in Fig. 5, this view showing two of the flaps upturned against the appropriate side walls of the box;

Fig. 7 is a section on the line 7—7, Fig. 4, upon an enlarged scale;

Fig. 8 is a detail plan view on a still larger scale, showing some of the brushes and wipers; and

Figs. 9 to 18 inclusive are details to be referred to, one of them, Fig. 10, being in perspective.

The machine frame 1, of suitable shape and

construction to carry the various parts, is provided, see Fig. 1, with bearings for a drive shaft 2, upon which is loosely mounted a belt pulley 3. This belt pulley constitutes one member of a friction clutch, the other member of which is a conical disk 4 splined upon the shaft 2, and normally pressed by a spring 5 into frictional driving contact with the belt pulley 3. To withdraw the friction disk from driving contact with the pulley, said disk is provided at one side the shaft with a clutch rod 6 mounted to slide longitudinally in a direction parallel with said drive shaft, said clutch rod being in turn controlled by a bell crank lever 7 fulcrumed at 8 on the frame. The horizontal arm of said bell crank lever receives a slide pin 9 mounted in a block jointed to the upper end of an arm 10 rising from a horizontal shaft 11 fulcrumed in brackets upon the frame, and in turn provided with a suitable treadle lever 12.

Normally the clutch spring 5 presses the clutch disk to the right into engaging contact with the pulley 3 against the weight and resistance of the several levers described, but said disk may be withdrawn from contact with its driving pulley by depression of the horizontal arm of the bell crank lever 7 which, see Fig. 2, is accomplished by a segmental cam 13 secured upon the barrel cam 14 fast upon the vertical cam shaft 15 mounted in bearings in the frame. Rotation of the barrel cam 14 causes the inclined leading edge of the segment 13 to depress the pin 9, Fig. 1, which underlies it, and thereby to depress the horizontal arm of the bell crank 7, and through the operating rod 6 withdraw the clutch disk from operating contact with the pulley 3 and arrest rotation of the main shaft and cam shaft referred to. To release the clutch, the foot treadle 12 is depressed, thereby through the shaft 11 and upright arm 10 to withdraw the pin 9 longitudinally from beneath the segmental cam 13, whereupon the clutch spring will press the clutch disk into engaging contact with the pulley, and at the same time will turn the bell crank lever into position with said pin 9 above the lower edge of said segmental cam, but outside the latter. When the treadle is released, the pin 9,

pressed by a spring surrounding it which is not shown, springs against the side of said segmental cam 13 and remains so pressed until said cam shall have been rotated past it, 5 whereupon said pin is further pressed inward into the path of said cam, so as to be engaged by its inclined leading end toward the close of a complete rotation and again depressed to arrest the driving movement as 10 before. Thus the construction is such that when once the foot treadle is touched, it releases the machine for a single complete rotation of the drive shaft, whereupon said shaft is automatically stopped until said treadle 15 is again depressed to release it.

By retaining the foot pedal depressed, the machine will continue without interruption for a succession of turns or cycles, and this 20 is frequently done when the work is such or the skill of the operator such as to make it practicable.

The vertical cam shaft 15 is driven from the main or clutch shaft through a worm wheel 16 thereon, Fig. 2, and a worm 17, Fig. 25 1, on the clutch shaft.

Upon the upper end of the cam shaft 15, see Fig. 1, is mounted a barrel cam 18, containing two cam paths 19 and 20. The cam 19 receives a roller stud 21 upon the side of 30 a lever 22 fulcrumed at 23 in an arm of a bracket 24 on the frame, and is provided at its short end with a weight 25 to aid in balancing and taking up slack in the motion.

At its opposite or free end, said lever 22 35 is provided with a roller stud 26, which may be clamped in adjusted position by a clamping device 27 in the slotted end of a link 28. This link is jointed at its upper end at 29 to a vertical slide bar 30 mounted to slide in 40 bearings or ways 31 in the arm 32 of the bracket 24 referred to.

At its lower end said slide bar 30 is provided with a cylindrical extension 33 carrying at its lower end, see Fig. 7, the lower 45 member 34 of a two-part presser, the other part 35 of which rests normally upon and effectively as a part of it.

The upper presser member 35, Fig. 7, is secured to a cross-head 36 which, see Fig. 1, 50 is carried by and upon the lower ends of two parallel slide rods 37.

These slide rods are mounted to slide at their lower ends in a head 38 secured to the lower end of the slide bar 30, also in bearings 55 in said arm 32, and at their upper ends are connected by a cross-head 38'.

The top cross-head 38' connecting the slide rods 37, see Fig. 1, is connected by a spring 39 with said slide bar 30, so that while said 60 slide rods and the heads connecting the same are free to move with the slide bar 30 as the latter is moved vertically by the lever 22, said slide rods are permitted a movement independent of said slide bar, under conditions 65 that will be hereinafter described.

During a certain part of the vertical movement of the two-part presser 34, 35, said parts move as a unit, but at times they are separated, and this separation is controlled by said spring 39, which brings the two parts 70 together again at the appropriate time.

The bracket arm 32 also has bearings for two additional slide rods 40 which, at their lower ends, see Fig. 1, are connected by a horizontal yoke 41, made U-shape to span the slide bar 30 and slide rods 37 already described. This U-shaped yoke 41 carries in its arms the oppositely extended bars 42, upon which are adjustably mounted the heads 43, in which are adjustably held the short vertical rods 44. These rods 44 have secured to their upper ends the ejectors 45, which depend through both presser members 34, 35. While normally they remain in position concealed within said presser members or one of them, at times these ejectors may be projected downward to eject or remove from the presser the completed covered box that may be carried thereon as the latter are elevated at completion of the covering operation. 80 This will be later described more in detail.

The ejector carrying yoke 41 is actuated by a link 46, shown mainly in dotted lines, Fig. 1, which is jointed at its upper end to a lever 47 fulcrumed at 48 on an arm of the bracket 24, and provided at its opposite end with a roller stud 49 which travels in a path cam 20 heretofore referred to, in the barrel 18.

Said path cams are so shaped as to give to 90 their respective levers and the parts controlled thereby the necessary movements to be hereinafter described in detail.

Beneath the presser, see Fig. 1, stands the yielding platen 50 faced with a felt or other suitable covering 51, which platen is mounted upon the upper end of a tubular column 52. Standing within and carrying this column is a telescoping support 53, the latter seated upon the base of the machine and containing a spring 54 which extends upward within and to carry the upper telescoping member 52, and through the latter the platen column 52. Upward spring pressed movement of the member 53 and the platen carried thereon is limited by a collar 55, Fig. 1, which seats against the under side of the base portion of a bracket 56 mounted in the frame.

The box B and the paper blank P that is to be used to cover it are fitted upon the elevated presser as indicated in Fig. 1 and, during the subsequent downward movement of the presser, are clamped between the latter and the spring supported platen 50, which latter yields before the descending presser to permit the latter to carry the box and blank into one or another of its successive depressed positions, as will be more fully hereinafter described.

Before describing the wiper mechanism, reference should be made to Figs. 5 and 6, 130

where are shown the octagonal box B, herein used as an example of a box or cover having oblique walls, and the paper or other blank P which is to be used for covering the box. 5 The blank is coated at its inner top surface with an adhesive and is applied to the box as shown.

It will be observed that the box comprises the pairs of parallel end walls b, b, parallel 10 side walls b', b', and the pairs of oblique walls b², b². The bottom of the box is indicated at b³.

The paper or other cover blank P comprises a central portion p³, Fig. 7, from which 15 radiate the pairs of flaps p, p, and p', p', Fig. 5, and the pairs of oblique flaps p², p².

It will be observed that the opposite flaps p, p, are provided at their side edges with wing portion p⁴, p⁴, their edges tapering 20 gradually inward from their respective ends to the points p⁵ below which they taper more abruptly to the actual bases of the flaps. The oblique flaps p² are provided with wings p⁶ at one of their side edges only, the edges 25 of said wings tapering inwardly toward their bases as do the wings p⁴, and having the same breaks at p⁵, below which the taper is more accentuated, while the remaining flaps p¹ have their side edges tapered inwardly as 30 at p⁷ from the bases thereof to their extremities.

The problem is to wipe or upturn the several flaps against the side walls of the box or its equivalent, and to overlap the edges thereof at the corners where the side walls meet, and then to inturn the free ends of the upturned flaps over and downward against the inner faces of the box walls.

This is accomplished by first upturning 40 the opposite broadened flaps p, p, against the corresponding walls b, b, of the box, as indicated in Fig. 7, and then bending the wings p⁴ of each flap around and against the corresponding portions of the adjacent oblique 45 walls of the box; next the pairs of oblique flaps p², p², are similarly wiped upward against the oblique walls b² of the box, and with their straight inwardly tapering edges overlying the previously inwardly bent wing 50 portions p⁴ of the previously folded flaps p, and with their single wings p⁶ wiped around and bent against the adjacent portions of the walls b', b', of the box; and finally the inwardly tapering or narrowing straight- 55 edged flaps p¹, p¹, are folded upward against the side walls b¹, b¹, of the box, and against the bent-over wings p⁶ of the oblique flaps p². Thus all the side walls of the box will be 60 perfectly covered with the edges covered by the wing portions of such flaps as are provided with the same.

These upturned flaps will project at their upper edges above the rim of the box and remain to be pressed inward toward the center of the box and downward against the

inner faces of the side walls to complete the covering. The foregoing are the steps that are to be performed by the mechanism that will now be described.

Referring to Figs. 4 and 7, at the level of 70 the platen when the latter is in its elevated position, opposite the two side walls of the platen that receive the side walls b, b, of the box to be covered, are two wiper brushes 57, which are shown as comprising respectively a plurality of small bunches of bristles arranged in horizontal series to constitute in effect a single brush of the length of the series, said wiper brushes standing directly below the flaps of the blank that are to be upturned against the box walls at the moment said blank, with its box, gripped between the presser and the platen, begin their descent at the center of the machine.

The brushes 57 are mounted in suitable 80 holders 58 connected by joints or hinges 59 with blocks 60, adjustably secured by clamping screws 61 upon the upstanding pins 62. These pins 62 are carried in the ends of arms 63 slotted at their opposite ends at 64 to receive the clamping screws 65, by which said arms are adjustably secured to the adjustable but stationary heads 66 mounted upon the frame. These heads are slotted at 67 to receive the clamping screws 68 on the frame, 90 which permit the heads to be moved to and from the platen to accommodate boxes of different sizes.

As the presser is depressed by its cam, carrying before it the platen with the box and 100 covering blank gripped between them, the stationary wiper brushes 57, see Fig. 7, will engage the extended flaps p, p, and wipe them upward into their dotted line positions close against the outer faces of the walls b, b, of the box, to which said flaps, having been previously pasted, adhere instantly upon making contact therewith.

The brush holders 58 remain rigid against the wiping action as the flaps are wiped upward against the box walls, but are free to turn freely upward about their hinges 59 during the subsequent ascent of the platen with the covered box thereon, to avoid undue scraping or frictional contact with the paper 110 covered box walls.

The action described has upturned the flaps p, p, as in Fig. 6, but the wing portions p⁴ remain projecting beyond the oblique walls p², as in Fig. 6, and must be inturned 120 against said oblique walls before the oblique flaps p² can be upturned against their corresponding oblique box walls.

To accomplish this inturning of the wings p⁴, I have provided, see Fig. 8, a pair of wing wipers 69, shown as vertical plates corrugated at their inner faces, as at 70, and arranged at a level slightly below the level of the brush wipers 57, as will best appear from dotted lines, Fig. 7.

Each wing wiper 69 is made vertically adjustable at 71, Fig. 9, in a head 72 fast on the end of one of the horizontal carrying rods 73. This carrying rod 73 is longitudinally adjustable in the head 74 on the vertical rod 75, which in turn is vertically adjustable in the head 76. The head 76 is hinged about a vertical pivot 77, Fig. 9, in another head 78 adjustable on and along the horizontal squared bar 79. This horizontal squared bar 79, see Fig. 7, is carried by a yoke 80 on two horizontal slide rods 81 mounted in lugs 82 on the head 66 already referred to as adjustably mounted in the frame.

By means of the adjustments described, the heads 66 upon opposite sides of the box may be brought toward or from each other to accommodate varying dimensions of box in that direction, and the heads on the sides 20 of the box may also be adjusted outward or from each other to accommodate different dimensions of the box in that direction.

In whatever properly adjusted position they may have been set, as the box with its 25 covering flaps p , p , upturned as in Fig. 7, is depressed by and between the presser and platen, see Fig. 8, the projecting flap wings p^4 will be depressed between the stationary wipers 69 described, which latter will inturn 30 said wings p^4 against the adjacent portions of the oblique walls of the box, to which said wings will adhere.

The wing wipers 69 just described, see Fig. 8, first meet the descending narrow neck 35 portions of the blank flaps p , p , close to the points at which they join the central portion of the covering blank, so as to wipe said narrow wing portions against the oblique walls of the box. By thus engaging the 40 narrow portions of the wings near the bases of said flaps, the entire flaps are swung around into what as a rule will be suitable firm contact with the oblique box walls but, to make certain that the wider portions of 45 said wings are firmly and smoothly pressed against said oblique box walls, it is desirable that in the further descent of the box and cover flaps, said wing wipers be moved inward to cause their wipers to act upon the entire areas of the wider portions of said wings. The mounting of the wing wiper carrying heads 76 upon the vertical pivots 77 permit said wipers to spread as they are pushed inward to reach and smooth the widest 55 portions of the covering wings, they being held yieldingly in contact with said wings during the smoothing operation by the coil springs 85, see Fig. 9, surrounding the pivot 77. These springs serve also to 60 return the wipers to their normal positions, Fig. 8, when they are withdrawn from the spreading oblique walls of the box.

To move said wing wipers bodily inward thus to cause them to spread and smooth the 65 covering wings upon the oblique box walls,

the squared rods 79, Figs. 8 to 10 inclusive, are moved bodily inward at the proper times, carrying with them the heads and wing wipers described by the following mechanism:

Referring to Figs. 2 and 3, the horizontal slide rods 81 are connected at opposite sides of the machine by a cross bar 83 held in adjusted position upon said slide rods, between the collars 84 fastened upon the guide rods by clamping screws 85. At an intermediate 75 point on said cross bar 83 is jointed at 87 a link 88, which at its opposite end is jointed at 89 to an arm 90 fast on a horizontal shaft 91 mounted in the frame of the machine.

The shafts 91 at opposite sides of the machine are provided respectively with depending arms 92, provided with pins 93, to which are jointed the ends of the connecting rods 94 jointed at their opposite ends at 95 to the opposite ends of a T-shaped lever 96 fulcrumed upon a stud 97 on the frame. The depending arms 92 on the shaft 91 described are provided with a plurality of holes at different radial distances from the shafts 91, into which the pins 93 may be placed to vary the length of oscillations of said arms by a given throw of the connecting rods 94, and similarly the lever 96 at its ends is provided with a series of holes for the joint pins 95 by which to vary the longitudinal throw 85 of the connecting rods by and from given oscillations of said lever 96.

The horizontal or intermediate arm of the T-shaped lever 96, which is marked 98, carries at its free end a roller stud 99, which 100 enters a cam groove 100 in the barrel cam 14 previously described.

Rotation of the cam shaft 15 will thus oscillate the T-shaped lever 96, and through the connections described will cause the wing 105 wipers 69, Fig. 8, at the proper times to advance inwardly to cause the wing wipers to smooth the wing flaps p^4 against the spreading oblique side walls of the box. Thus as the box descends, these spreading wings are 110 wiped smoothly upon the oblique box walls by a wiping action beginning at the bottom and close to the angle where they are bent around the corner of the box, and extending upward and further inward by a natural wiping action, such as would be performed 115 if said wings were turned and smoothed by hand.

The next step, as stated, is to upturn the 120 oblique flaps p^2 against the obliquely standing box walls b^2 , with their straight tapering edges overlying the overturned wing portions of the previously folded flaps p .

This is accomplished in the further descent of the presser and platen with the box and covering blank still firmly gripped between them. Referring to Figs. 4, 9 and 11 to 13 inclusive, I have provided at the next level below the wing wipers 69 described, 125 obliquely positioned stationary brush wipers 127

101. These brushes are clamped in holders 102 horizontally pivoted at 103, see Fig. 11, in heads 104 adjustably secured to the down-turned lower ends of the holding rods 105, see Fig. 13. These holding rods 105 are adjustably mounted in blocks 106, see Fig. 11, on the upper ends of the short rods 107. There are two of these vertical rods 107 at each side of the machine, holding respectively the oblique wiper brushes at that side of the machine, and said pairs of rods, see Fig. 4, are respectively, adjustably mounted in the ends of arms 108 on adjustable heads 66 heretofore referred to.

15 Referring to Fig. 4, it will be seen that by 15 rotatively and slidingly adjusting the brush carrying heads and rods, one relative to another, the oblique wiper brushes 101 may be given any desired obliquity in any desired 20 position and at any desired level, properly to act upon the oblique flaps and box walls presented to them. The same is true with respect to the wipers 69 and other wipers of the machine designed to act upon the oblique 25 flaps and box walls.

Descent of the presser and platen carrying the box and covering blank between them, thus operates through the stationary oblique wiper brushes 101 to upturn the oblique flaps 30 of the covering blank, but the wings p^6 at one of the edges of said flaps will be left protruding beyond their adjacent box corners as shown in Fig. 12.

To turn these wings inward against the 35 adjacent portions of the box walls, I have provided wing wipers 111, shown best in Figs. 10 and 14, which act similarly to the action of the wing wipers 69 heretofore described.

40 Each of said wing wipers 111 is adjustably mounted in the block 112 on the end of the horizontal rod 113 adjustably mounted in the head 114 on the lower end of vertical rod 115. This vertical rod 115 is adjustably 45 secured in the block 116 on the end of the horizontal rod 117 adjustably secured in a lug on the swinging head 76 heretofore described as carrying the wing wiper 69.

When once these wing wipers 111 are properly 50 adjusted to the box and blank to be acted upon, they will operate in the further descent of the box and covering blank to engage the oblique flap wings p^6 and turn them against and smooth them upon the adjacent side 55 walls of the box, precisely as did the wing wipers 69 referred to.

The same inward or closing movement of the squared shafts 79 that carried the wing wipers 69 inward against the flap wings p^4 60 is continued to carry the wing wipers 111 at the lower level into engagement with the wings p^6 , to wipe them around the box corners, but the wiper heads 76, after having spread to permit the inwardly closing wiper 69 to perform their work, are freed by the

descending box to spring back to their original positions before they are a second time turned to permit the spreading of the wing wipers 111 in the subsequent turning and wiping of the wings p^6 , the stationary, 70 oblique wiper brushes performing their work between the times of operation of the wing wipers 69 and the wing wipers 111. In practice the action is speeded up somewhat by causing the stationary oblique brush wipers 101 to begin their work before the wing wipers 69 have completed their work, and the wing wipers 111 may begin to function before the wiper brushes 101 have completed their work. This capacity for one operation 80 to overlap another is particularly useful in handling deep boxes.

In the further descent of the presser and platen with the box and covering blank gripped between them, the latter meet the 85 final stationary brush wipers shown in Fig. 15 and marked 118. Each of these brush wipers, like those previously described, is mounted in a head 119 horizontally pivoted at 120 to a block 121 adjustably mounted 90 upon the upright pin 122. Each pin 122, see Fig. 4, is carried in the end of an arm 123 slotted at 124 to receive the clamp screw 125, by which said arm is adjustably mounted 95 upon the bracket 126. This bracket 126, see 95 Fig. 1, is adjustably mounted upon the frame of the machine and is adjustable inward and outward thereon by the clamping device 127. One of these brackets and its accompanying brush wiper is mounted in the frame at each 100 side of the box, that is to say, the two are mounted at opposite sides of the machine, as best appears in Fig. 4.

As the brush and its blank are carried 105 downward between these two final brush wipers, the latter engage the two remaining unfolded flaps p^1 and fold the latter upward and against the remaining two sides of the box, as best appears from Fig. 15.

Since the last two flaps p^1 that are upturned 110 have straight inwardly tapering side edges with no overlapping wings to be handled, there is no occasion for subsequently acting wing wipers.

All the covering flaps have now been upturned against the side walls of the box and stand with their upturned edges extending substantially above the rim of the box walls and above the presser, as shown in Figs. 13 115 and 15.

In the operation of the machine, the presser and platen continue their descent with the box—its walls now covered—still firmly clamped between them, below the positions shown in Fig. 15, for the purpose of inturning the flaps about the rim of the box wall.

In this further operation of the machine, the two members of the presser no longer move as a unit; the lower member 34, actuated by the bar 33, continues its descent push- 125 130

ing before it the platen with the box still gripped between them, but the upper presser member 35 is arrested as illustrated in the detail, Fig. 16. The upper presser member, as stated, see Fig. 1, is secured to the lower ends of the parallel rods 37, which are connected at their upper ends by the cross-head 38', from the back of which depends a stop rod 38", shown in dotted lines, Fig. 1. As the 10 presser bar 33 continues through the final portion of its descent as described, the stop rod 38" meets the top of the now stationary lever 47, which prevents further descent of the upper presser member, causing the further descent of the lower presser member to open up the space between the upper and lower presser members, as shown in Fig. 16. At the 15 same time the spring 39, Fig. 1, is put under tension, for the purpose of causing the upper presser member to follow and overtake the lower presser member when the former is released for that purpose.

By the time the lower presser member 34 has reached its lowest position, as shown in 20 Fig. 16, a sufficient space has been opened up between the two presser members to permit the upstanding ends of the covering flaps to be folded inward over the rim of the box wall, as shown in Fig. 17, whereupon said lever 47, 25 Fig. 1, is depressed by its cam to permit said spring 39 to pull the cross head 38' and the upper presser member depending therefrom downward to overtake and close upon the lower presser member, and in so doing to bend 30 downward before it the horizontal inturned ends of the covering flaps and place the latter against the inner faces of the box wall, as shown in Fig. 18. Before the upstanding ends of the covering flaps are turned inward, 35 as described, and of course before the upper presser member descends to close the folding space, as described, it is desirable to straighten up the box walls accurately into desired alignment, according to the desired 40 shape of the box. Since the presser is given the desired outline of the box and is accurately made to the dimensions desired for the interior of the box, this straightening of the side walls is conveniently obtained by pressing 45 said walls firmly against the side walls or edge of the presser. For clearness, in Figs. 16 to 18, the paper covering is shown of exaggerated thickness, which results in a clearance between the lower presser member and the box 50 wall, which would not appear in practice.

To accomplish this, see Fig. 7, I have provided side wall pressers 128, which are of a size and shape to fit the side walls b' of the box and the adjacent oblique walls b^2 at each 55 side of the box. Each side wall presser 128 is lined with felt or other suitable material 129, and at its outer face is provided with a rib 130 which is received in a socket 131 and is there clamped by one or more set screws 132. 60 The socket 131 is yieldingly carried by and

between two rods 133 mounted to slide in the frame brackets 66, as is usual in machines of this character.

Mounted in suitable bearings also in said brackets 66 is a horizontal shaft 134, Fig. 7, 70 upon which is mounted an oscillatory arm 135, which is provided at its hub with two cam projections 136, 137, adapted respectively to engage a lug shown as spanned by them and mounted upon the presser head 131. 75

When the head 135 is oscillated to the right, Fig. 7, the cam 136 will engage the lug referred to, and will push the presser member 128 to the right a sufficient distance to straighten up the box sides preparatory to in-folding of the ends of the flaps above the same. Upon the return oscillation of said member 135 in the opposite direction, said presser member will be released and will spring back to its position shown in Fig. 7, 80 and will immediately thereafter be engaged by the cam lug 137, which is a little higher than the lug 136, and will be again moved to the right and through a slightly greater distance than before, to compress the covering upon the outer and inner faces of the box wall, as will be more fully described 85 presently.

It is to be understood that the presser means just described is reproduced at all 90 four sides of the machine, to operate upon the opposite sides of the box.

Practically simultaneously with the first movement of the presser 128 described for straightening up the box sides, the upstanding ends of the covering flaps will be wiped inward to a horizontal position in the space between the separated upper and lower presser members. This is accomplished by horizontal, inwardly moving wiper plates or 100 wipers 138, one at each side of the box, that is to say, one above and operating in conjunction with each of the pressers 128. 105

Each wiper 138 is clamped in a cross head 139 mounted upon the ends of horizontal slide rods 140 carried in bearings upon the bracket arms 66. Between the slide rods 140 the cross head 139 is connected by a link 141 with the oscillatory head 135, so that as said head is oscillated to cause its cam 136 to impart wall straightening movement to the presser 128, said head through the link 141 will simultaneously push the wiper 138 inward to fold the upstanding end of the covering flap that stands in front of it inward and downward into a horizontal position overlying the lower presser member 34 then in its lowermost position, as shown in Fig. 17. 115

Upon the withdrawal of the presser 128 and wiper 138 by return oscillatory movement of the head 135, the upper presser member 35 will be released from its elevated position by further downward movement of the lever 47, Fig. 1, that had supported it and, 120 125 130

actuated by the spring 39, will follow the downward movement of said lever, causing said upper presser member to engage the in-turned covering flap ends and turn them 5 downward and outward against the inner faces of the upper portions of the straightened box walls, as shown in Fig. 18. This final downward movement of the upper presser member 35 takes place during the first part 10 of the withdrawal movement of the presser 128 and wiper 138 and, with said presser member still in its lowermost position, the continued return oscillatory movement of the head 135 for further withdrawal of the presser 128 and wiper 138, will cause the lower and higher cam 137 on said oscillatory head to engage the lug on the presser head and push the latter a second time inward and farther than before, to press the now fully 20 covered box wall tightly against the upper and lower presser members within, to smooth out and finally set the covering upon the box wall.

Referring to Fig. 7, each oscillatory head 25 135 is actuated by a link 142 from a vertically sliding bar 143 mounted in a bearing in said bracket arm 66. Said slide bar 143 is socketed at its lower end to receive the end of the horizontal arm 144, to which said head 30 is adjustably secured by a clamp 145.

There are four of these horizontal arms 144, the same radiating from a common head 146, Fig. 1, mounted to reciprocate vertically upon a tubular support 147 resting upon the 35 frame or more strictly upon the face of the bracket 56 which is carried by the frame. The platen supported column 52 slides within this tubular support 147. Said head 146 is raised and lowered by a link 148, Fig. 40 1, connected with one end of a lever 149 fulcrumed at 150 in said bracket arm 56, and carrying at its opposite end a roller stud 151 which enters a cam groove 152 in the barrel cam 14 earlier described.

When said cam is rotated by the cam shaft 45 to cause the various motions to function, said lever 149 is oscillated at the proper times to raise and lower the head 146, and its four 50 rotating arms 144, to cause the box wall pressers and final infolding wipers to function as described.

After the upturned flap ends have been inturned between the presser members and downturned by the closing of the upper presser member within the box down upon the lower presser member, and the accompanying pressing of the covered walls tightly against the presser edges, the presser rises with its members still closed upon each other 55 within the covered box, the spring supported platen following it still holding the covered box clamped tightly between it and the presser until the latter reaches its most elevated position, Fig. 1, limited by the collar 55, Fig. 60 1, below the sliding head 146, at or about

which time the now covered box in its further rising movement meets the lower ends of the 70 ejector rods 45, Fig. 1, which, meanwhile, have been lowered into proper position, so that the continued elevating movement of the presser will cause the latter to be lifted out from and clear of the covered box. The box will be held upon the platen by and against the ejectors 45 until the presser has cleared it, when the box is thrown out to one side preparatory to introduction of a new box having a new covering blank adhering thereto for a repetition of the covering movement 75 heretofore described.

This final ejecting or throwing out of the covered box to make way for a new box to be covered is accomplished, see Fig. 1, by a horizontal throw-out rod 153 mounted to slide in the frame arm 24 and actuated by a spring 154. Said rod 153 is moved to the right, Fig. 80 1, to compress its spring by an arm 155 carrying a roller stud 156 acted upon by a horizontal cam 57 on the cam shaft 15. In the rotation of said shaft 15, said rod 153 is moved gradually to the right to compress its 85 spring and, at the appropriate time, after the covered box has been freed as described from its contained presser, said cam releases the roller stud 156 and permits the spring 154 to impart a quick throwout movement of the rod 153, to the left, Fig. 1, to cast the box 90 out of the machine into a suitable receptacle provided therefor.

To summarize the steps in the covering of a box in pursuance of my invention, assuming the parts to be in their positions, Fig. 1, the operator takes a box blank such as shown in Fig. 5, with the pasted blank previously applied to the bottom thereof and adhering with substantial continuity throughout its middle 100 portion to the bottom of the box, and places or fits the same from beneath upon the elevated two-part presser, the parts of the presser being closed one against the other, as indicated.

The presser now descends until the box with its adhering covering blank meets the spring-supported platen, after which the further descent of the presser carries the platen before it in its downward travel, with 105 the box and blank firmly held between them.

Shortly after the presser with the box and covering blank thus meet the platen, the descending movement will cause the stationary wiper brushes 57, Fig. 7, to engage the 110 horizontally projecting flaps p , p , and turn them upward against the corresponding box walls. Immediately thereafter in the further descent of the presser and platen, the wing wipers 69, Fig. 8, already moving or about 115 to move inward, engage the wing portions p^4 of the covering flaps p , p , and turn the wings p^4 , p^4 , against the oblique walls and smooth said wings upon said walls.

In the continued descent of the presser and 120

platen, the oblique brush wipers 101 meet the four horizontally projecting oblique flaps p^2 and turn them simultaneously upward against and to adhere to the oblique walls of 5 the box, immediately following which the oblique wing wipers 111 will engage the wings p^6 of the covering flaps p^2 , and in the further descent of the presser and platen, combined with the inward movement of the 10 wing wiper mechanism, will turn and smoothly wipe said wings p^6 around and upon the remaining side walls of the box. As the presser and platen continue their descent, the remaining pair of side flaps p' will be engaged by the final brush wipers 118, Figs. 4 15 and 15, and will be wiped upward against and to adhere to the remaining side walls of the box.

As said presser continues in its descent, the 20 upper presser member is arrested by contact of its stop 38*, Fig. 1, with the now stationary cam lever 47, so that the lower presser member carrying the box and platen before it, separates from the upper presser member, see 25 Fig. 16, leaving a space into which the infolding wipers 138, by their advancing or closing movement, may turn the upstanding ends of the several covering flaps, simultaneously with the first or preliminary pressing movement of the pressers 128 against and to straighten the box walls.

As the pressers and infolding wipers withdraw, the descent of the cam lever 47 to position the box ejectors 45 ready to remove the 30 box from the presser when the latter approaches its most elevated position, releases the upper presser member 35, permitting the latter to descend upon the infolded flap ends, to turn the latter downward and to press them 35 against the inner faces of the box walls, as in Fig. 18, whereupon the pressers 128 are given a second and final inward pressing movement to press the box walls now covered without and within, firmly against the side edge walls 40 of the two-part presser, finally to set the covering upon the box wall. Thereafter the presser rises followed by the platen, taking with them the now covered box, until the platen reaches its most elevated position, 45 whereupon the presser leaves it and leaves the box on the platen carrying the box, being there held by the ejector rods 45, after which the box is thrown out of the machine.

55 My invention is not restricted to the embodiment herein disclosed but may be varied within the scope of the claims.

Claims:

1. A machine for covering boxes and the 60 like that have oblique side walls, comprising in combination supporting means for the box and the covering blank, wipers mounted for oblique operation to wipe the cover against the oblique wall or walls, and one or more 65 wing wipers having both inward and oblique

movements cooperating with said oblique wall wipers.

2. A machine for covering boxes and the like that have oblique side walls, comprising in combination wipers obliquely standing to 70 lay the covering material against said oblique box walls, and one or more wing wipers having both inward and spreading movements cooperating therewith.

3. A machine for covering boxes and the like that have oblique side walls, comprising in combination obliquely mounted wipers to 75 lay the covering material against said oblique box walls, one or more wing wipers cooperating therewith, and means to impart both inward and oblique movement to each of said wing wipers.

4. A machine for covering boxes and the like that have oblique side walls, comprising in combination obliquely mounted wipers to 80 lay the covering material against said oblique box walls, one or more wing wipers cooperating therewith, and means to impart both inward and spreading movement to each of said wing wipers.

5. A machine for covering boxes and the like that have oblique side walls, comprising in combination obliquely mounted wipers to 85 lay the covering material against said oblique box walls and one or more wing wipers cooperating therewith, means to impart both inward and oblique wiping movement to each of said wing wipers, and means to impart relative movement to the box with its covering material and said wing wipers.

6. A machine for covering boxes and the like that have oblique side walls, comprising in combination a presser and means to depress it, an opposed yieldable platen, a set of wipers between which said presser and platen are depressed, one or more wing wipers arranged below said first mentioned wipers, obliquely arranged wipers standing below said wing wipers, one or more additional wing wipers below said obliquely arranged wipers, 100 final wipers at a still lower level, and means to impart to said presser and platen on the one hand and to said series of wipers on the other, relative movement to cause said wipers to act upon a covering blank held between 105 said presser and platen.

7. A machine for covering boxes and the like that have oblique side walls, comprising in combination a presser and means to depress it, an opposed yieldable platen, a set of wipers between which said presser and platen are depressed, one or more wing wipers arranged below said first mentioned wipers, obliquely arranged wipers standing below said wing wipers, one or more additional wing wipers 110 below said obliquely arranged wipers, final wipers at a still lower level, infolding wipers, and means to impart to said presser and platen on the one hand and to said series of wipers on the other, relative movement to 115 cause said wipers to act upon a covering blank held between said presser and platen.

120

125

130

cause said wipers to act upon a covering blank held between said presser and platen.

8. A machine for covering boxes and the like that have oblique side walls, comprising in combination a presser and means to depress it, an opposed yieldable platen, a set of wipers between which said presser and platen are depressed, one or more wing wipers arranged below said first mentioned wipers, one or more obliquely arranged wipers below said wing wipers, one or more additional wing wipers below said obliquely arranged wipers, final wipers at a still lower level, infolding wipers and wall straightening and pressing means, and means to impart to said presser and platen on the one hand and to said series of wipers on the other, relative movement to cause said wipers to act upon a covering blank held between said presser and platen.

20 In testimony whereof, I have signed my name to this specification.

RICHARD P. SECKENDORF.
